UNITED STATES PATENT OFFICE.

JAMES C. GASKILL, OF FAIRMONT, WEST VIRGINIA.

ADJUSTABLE BAR-COAL SCREEN.

1,351,563.

Specification of Letters Patent. Patented Aug. 31, 1920.

Application filed February 6, 1920. Serial No. 356,717.

To all whom it may concern:

Be it known that I, JAMES C. GASKILL, a citizen of the United States, and a resident of Fairmont, in the county of Marion and State of West Virginia, have invented certain new and useful Improvements in Adjustable Bar-Coal Screens, of which the following is a specification.

My invention relates to bar coal screens, and more particularly to adjustable coal screens of this type.

It has been the custom in coal screens of this type, when it was necessary to change the size of the screen, to remove the bars and replace them with the sized bars necessary to make the screen of the desired mesh. This is a long and tedious operation and requires considerable time. My invention embodies all of the desirable principles of a bar coal screen, but provides means for adjusting the size of the mesh without the necessity of removing and replacing the bars.

The objects of my invention are accomplished in devices very similar to the type of bar screen now universally in use, and embodies mechanism by which the size of the mesh may be varied automatically, by the simple operation of a cable and drum mechanism. By my invention, time and expense, which the use of the old type of bar screen necessitated, has been obviated and a more practical and efficient screen is the result.

With these and various other objects in mind, I will more specifically describe and point out the features of my invention in the specification and drawings, in which,—

Figure 1 is a top plan view of my improved adjustable bar coal screen, with one-half of the screen adjusted for small-sized mesh;

Fig. 2 is a side elevation of my invention;

Fig. 3 is a cross-sectional view taken on line 3—3 of Fig. 1;

Fig. 4 is a detailed sectional view of the pivotal connection of the lug-supporting members;

Figs. 5 and 6 are fragmentary perspective views of the two ends of the removable bars;

Figs. 7 and 8 are modifications of the bar-carrying lugs; and

Fig. 9 is a modification of the lug-carrying bars.

In the drawings, 1 indicates side beams upon which my screen is supported. These beams may be supported in any suitable manner, but as they form no part of my present invention I will not describe them in detail. Arranged transversely of these beams 1 are I-beams 2, here shown as four in number. These I-beams are rigidly secured to the beams 1 in any suitable manner. Supported transversely of these I-beams 2 and parallel with the beams 1 are three H-beams, the central H-beam 3 being rigidly secured to the I-beams 2 in any suitable manner, while the two outer H-beams 4 rest upon the I-beams 2 and are adapted to slide thereon. Upon these H-beams are pivotally supported the members which carry the removable bars which form the screen.

The bar supporting members are indicated by 5, and as shown more particularly in Fig. 4, one of these bars has its end bifurcated, as at 6, to receive the reduced end 7 of the other bar 5 to provide a pivotal connection. The screen bars are indicated by 8. Loosely mounted in each of the bars 5 is a series of screen bar-carrying lugs 9, which have reduced ends 10 forming a shoulder 11, which rests upon the upper face 85 of the bars 5. This reduced portion 10 of the lug 9 is loosely held in drilled holes 12 in the members 5. A pin 13 inserted in the projecting end of the lug 9 holds the lug in the member 5, but permits its oscillation 90 therein.

The upper end of the lug 9 has cut there-in a V-shaped slot 14, in which the lower edge of the screen bars 8 is adapted to rest. These screen bars 8 have at their opposite ends openings which permit them to be fastened in the lugs contained in the bar supporting members at either end of the screen.

By referring more particularly to Figs. 5 and 6, this bar securing means will be more readily understood. Fig. 6 shows the upper end of the screen bars having a bayonet slot 15. Fig. 5 shows the lower end of the screen bar 8 provided with a slot 16 ex-tending longitudinally thereof. Secured transversely of the slots 14 in the series of lugs at the two ends of the screens are pivot pins 16', shown more particularly in Fig. 4. In positioning these bars in the lugs, the slot in the lower end is designed to straddle the pivot pins 16' in the lug at the lower

end of the screen, while the pivot pin in the lug at the top of the screen is adapted to pass into the bayonet slot through the opening 17. The bar 8 is then shifted lengthwise, which will position the pivot pins in the inner ends 18 and 19 of the slots 15 and 16, respectively. The intervening lugs, or, in other words, the lugs contained on the bar supporting members other than the two end ones, are provided merely with the slots 14, and it is obvious that when the bars 8 are positioned as hereinbefore stated, they will be held securely by the lugs 9 and will retain their relative parallel position during the operation of the adjusting feature of the screen.

As hereinbefore stated, the central H-beam 3 is rigidly secured to the I-beams 2, and the inner ends of the lug supporting members 5 are pivoted to this stationary H-beam 3. By reference to Fig. 4, the manner in which this pivotal connection is made will be more readily understood. The lower end of lug 9 is made longer than the others, and its end 20 extends through a hole 21 drilled through one side of the H-beam 3, and a pin 22 passes through the end 20 of this lug 9 and secures the lug against vertical displacement. Interposed between the pivotal connection of the bars 5 and the top face of the H-beam 3 is a filler member 23, which allows sufficient clearance space between the bars 5 and the H-beam 3 to permit the lower ends 10 of the lugs 9 to pass the H-beam 3 when the screen 35 is operated for adjustment.

The outer ends of the lug supporting members 5 have a pivotal connection with the H-beams 4, as shown at 24. This pivotal connection is very similar to that described in Fig. 4, and reference to Fig. 3 will more clearly disclose this connection. The lug 9 is extended as in the case of the central pivotal connection, and has a pin passing through the extended end and under the flange of the H-beam 4 in exactly the same manner as that shown in Fig. 4.

From the foregoing it is evident that by moving the H-beams in an endwise direction, with the H-beam 3 as a pivot, the distance 50 between the screen bars 8 may be varied, these bars being held in their relative parallel position by the lugs 9, which oscillate in the holes 12 through the members 5 when such adjustment is being made.

55 In order to provide means for conveniently sliding these H-beams 4, I provide a cable and drum mechanism, which I will now describe. Mounted upon the outer sides of the H-beams 4 are brackets 25 supporting pulleys 26 and 26'. Mounted preferably upon the beam 1 are brackets 27, carrying pulleys 28 and 28'. I also provide a drum 29, having integral therewith a gear 30. This drum may be located in any suitable 60 place, and I have here shown it adjacent the

screen member. It is obvious, however, that with the cable connections, this drum member may be located at any convenient place. For operating said drum I provide a pinion 31, connected with a handle 32 and having a holding dog 33. A cable 24 has one end secured at some convenient point on the frame, here shown on the I-beam 2. From here it extends over the pulley 26, thence over the pulley 28, and from there around the drum 29, the cable continuing over pulley 28' and thence over pulley 26', secured to the slidable H-beam 4 and having its end secured to the frame, here shown at the same point as the other end of the cable. A turnbuckle 35 is provided for keeping the cable tight.

From the mechanism described above, it is obvious that by operating the handle 32, and thereby rotating the drum 29, the cable may be drawn in one direction or the other and thereby slide the H-beam 4 in either direction. By reference to Fig. 1 it will be seen that the drum and cable mechanism has been operated to slide the H-beam 4 to its lowermost position, thereby reducing the space between the screen bars 8. This drum and cable mechanism is duplicated on the other side of the screen, and as its operation which controls the other half of the screen is identical with the one hereinbefore described, no further mention of the same need be made.

It should be noted, however, that by extending the shaft carrying the drum 29 transversely of the machine, both drums might be carried by this shaft and the two drums operated simultaneously from one side of the screen.

In order to provide means for directing the coal upon the portion of the screen which can be used, I provide side plates 36 and 37, which, as shown clearly in Fig. 2, are supported above the coal bars 8 to form a clearance, so as not to interfere with the adjustment of these coal bars. Pivoted to a transverse bar 38 connecting the two side plates 36 and 37 is a plate 39. This plate directs the coal upon the screen and covers the portion of the screen not available for use by reason of the position of the screen bars after their adjustment for a smaller mesh, as clearly indicated in Fig. 1 of the drawings. This plate 39 is pivoted so that it may be raised, as shown in Fig. 2, to permit the withdrawal of the bars 8, should occasion for their withdrawal occur at any time. A transverse opening 40 is provided in the screen bars 8 for inserting a hook or other instrument for the purpose of withdrawing these screen bars.

The side plates 36 and 37 may be supported in any suitable manner, preferably upon the tipple with which these screens are usually associated, and I have here shown in dotted lines a portion of such tipple or other

structure 41, on which these plates are held by means of brackets 42.

A transverse plate 43 is shown at the lower ends of these directing plates 36 and 37, and I have shown this plate as supported by a transverse beam 44 extending across the beams 1.

I find it desirable in some instances to use other forms of lug 9, and by reference to Figs. 7 and 8 the exact form of these lugs will be readily understood. In Fig. 7 the lug 9, instead of having the reduced portion forming a shoulder, is provided with pin 45 which rests upon the upper face of the member 5, while a pin 46 extending transversely of the lug 9 secures this lug to the member 5, but permits its rotation. In the structure shown in Fig. 8 a collar 47 is formed upon the lug 9 and rests upon the member 5, while a pin 48 extending through the lower end of the lug retains it in the member 5. The two modified forms of lugs just described are oftentimes desirable, in that they are less expensive to manufacture, as they eliminate the necessity of turning the lug down to produce the reduced end, and therefore, while I have shown as my preferred form the lug with the reduced end, it shall be understood that either of these modifications may be substituted without departing from the spirit or scope of my invention.

I also find it desirable, when the dimensions of the screen are increased, or, in other words, in screens having larger screening surfaces than the one herein shown, to form the lug-carrying members in two parts, as shown very clearly in Fig. 9. In this form, instead of having the lug-carrying members of one piece, as shown at 5 in Fig. 4, I form this member in two parts, indicated by 49. In this form the central pivot is made by inserting a link 50 and using two of the lugs 9, here indicated by 51, as securing pins for one end of this link 50. It will be seen that these lugs 51 have their ends extended slightly below the other lugs, as shown at 52, and a pin 53 retains these lugs in place and rigidly holds the link 50 to the members 49. A lug 54, similar to lugs 51 except that the reduced portion is longer, extends through the members 49 and the free end of the link 50, and through a hole 55 drilled in the H-beam 3. A pin 56 passing through the projecting end of this lug 54 retains the lug in place and provides the proper pivotal connection for the members 49. In this construction it should be noted that the pins 13 of the lugs 9 bear on the lower face of the upper member 49, while the lug has an end projecting into an aperture 57 in the lower member 49.

I will now describe briefly the operation of my invention. When it is desired to change the size of the mesh of the screen, for instance, from that indicated in the sec-

tion A of the screen in Fig. 1 to that of the section B in Fig. 1, or any intermediate size, it is only necessary to operate the handle 32 and rotate the drum 29 in the proper direction to slide the H-beam 4 upon the I-beams 2 to reduce or increase the space between the parallel bar members 8. In Fig. 1 the section B has been operated to decrease the size of mesh, while the section A is shown as remaining at a large mesh. It is obvious in Fig. 1 that by operating the drum controlling section A so as to position this similarly to section B, the screen will be transformed to one of a smaller mesh. It is consequently also obvious that by reversing the operation the bars may be separated so as to provide a screen of large mesh. During the adjustment of the screen the members 5 move about the pivot point upon the H-beam 3, which is stationary, while the H-beams 4 slide in an endwise and slightly transverse direction, carrying with them the outer ends of the members 5. The lugs 9, as hereinbefore described, are mounted to oscillate in these members 5, and therefore, as the members 5 are moved the lugs rotate within the drilled holes 12, and the bars 8 are therefore retained in their spaced parallel relation.

It should also be noted that should any of the bars 8 become damaged or broken, they may easily be withdrawn by raising the plate 39 and inserting a tool into the aperture 40 in the bar 8, sliding the bar in an endwise direction so as to cause the pivot pin 16' to register with the opening 17 in the bayonet slot 15, whereupon this end of the bar 8 may be raised to free it from the lugs 9, and then by additional endwise movement the bar may be withdrawn so as to free the slot 16 from its pivot pin 16'. Thus, new screen bars may be inserted, and it should be noted that the use of nuts and bolts is dispensed with and the operation of replacing damaged screen bars made very simple.

The side plates 36 and 37, together with the plate 39, coöperate to direct the coal upon the portion of the screen which may be utilized as screening surface.

From the foregoing it will be seen that I have provided a bar screen which is simple in operation and embodies the features of the bar screen now universally in use. It should also be noted that various modifications may be resorted to without departing from the spirit and scope of my invention.

Claims.

1. In a device of the class described, a frame, comprising side beams and transversely disposed I-beams, a stationary, central, longitudinal supporting beam, transverse lug-carrying members pivotally supported upon the stationary central longitudinal beam, additional longitudinal beams pivotally supporting the outer ends of said

- transverse members, a multiplicity of spaced parallel bars, and lugs carrying said bars, said lugs being mounted upon said transverse lug-carrying members, and said 5 additional longitudinal beams being slidably supported by said transverse I-beams, as and for the purpose set forth.
2. In a device of the class described, a frame, comprising side beams and trans- 10 verse I-beams, a stationary central longitudinal supporting beam mounted upon said I-beams, a multiplicity of spaced parallel bars, lugs adapted to carry said bars, transverse members supporting said lugs, 15 said transverse members being pivoted to the stationary central longitudinal supporting beam, additional longitudinal beams pivotally supporting the outer ends of said transverse members, said additional beams 20 being slidably supported upon said transverse I-beams, and drum and cable means for sliding said additional longitudinal beams transversely of said I-beams, as and for the purpose set forth.
- 25 3. The combination with screen bars and means for supporting said bars in spaced parallel relation, including rotatable lugs, of transverse members for carrying said lugs, a central stationary supporting beam 30 providing a pivot for the transverse members; and means for independently swinging the transverse members on either side of the central supporting beam to vary the distance between said screen bars said means comprising a cable and drum, as and for the purpose set forth.
4. In a bar screen, a multiplicity of spaced parallel bars, lugs adapted to carry said bars, transverse members supporting 40 said lugs and allowing the oscillation of said lugs, a stationary central longitudinal supporting beam providing a pivot point for said transverse members, additional longitudinal beams pivotally supporting the 45 outer ends of said transverse members, and means for independently moving these last-named members, for the purpose described.
5. In a device of the class described, spaced parallel screen bars, lugs for carrying said screen bars, said lugs having V-shaped openings to receive said screen bars, transverse lug-carrying members provided 55 with series of openings for receiving the lower ends of said lugs and permitting oscillation of said lugs therein, a longitudinal beam providing a stationary pivot for the inner ends of said transverse members, additional longitudinal beams supporting the outer ends of said transverse members, and 60 means for moving said last-named beams to vary the distance between said screen bars, as and for the purpose set forth.
6. In a device of the class described, 65 spaced parallel screen bars, lugs for carrying said screen bars, said lugs having V-shaped openings to receive said screen bars, transverse lug-carrying members provided with series of openings for receiving the lower ends of said lugs and permitting oscillation of said lugs therein, a longitudinal beam providing a stationary pivot for the inner ends of said transverse members, additional longitudinal beams supporting the outer ends of said transverse members, and 70 cables passing around said drum and over said pulleys for moving said beams, as and for the purpose set forth.
7. The combination, in a bar screen com- 75 prising a multiplicity of spaced parallel bars and provided with means for supporting said bars and for varying the distance between said bars while retaining them in spaced parallel relation, with side plates 80 suspended above said screen bars, a plate pivotally supported between said side plates adapted to direct and confine the coal upon the available screening surface of said screen, said side plates and pivotally supported plate being mounted so as to provide a clearance to enable the screen to be adjusted, substantially as described.
8. In a device of the class described, screen bars, lugs for carrying said screen 90 bars, transverse members supporting said lugs, V-shaped slots formed in the upper end of said lugs, transverse pins bridging these V-shaped slots in the series of lugs carried by the transverse members at both 95 ends of the screen, retaining slots formed in both ends of the screen bars adapted to straddle said pins and retain said bars upon the lugs, substantially as described.
9. In a device of the class described, a 100 multiplicity of screen bars, means for removably supporting said screen bars, comprising lugs, said lugs having depending ends, transverse members providing supports for said lugs and allowing the lugs 105 to oscillate therein, and means co-operating with the depending ends of the lugs for retaining them in position, substantially as described.
10. In a bar screen, a multiplicity of 110 spaced parallel bars, means for removably supporting said bars, comprising transverse lug-carrying members, lugs supported upon said lug-carrying members, said lug being capable of oscillating and having formed 115 therein V-shaped openings to receive the screen bars, and means for swinging the lug-carrying members to vary the distance between the spaced parallel bars, as and for the purpose set forth.

JAMES C. GASKILL.
